COLLAPSIBLE BOX CONSTRUCTION

Elmer V. Smith and Emanuel T. Dunn,
Philadelphia, Pa.

Application September 30, 1949, Serial No. 118,748

4 Claims. (Cl. 217—16)

1

The present invention relates to new and useful collapsible containers and particularly to relatively large, rigid, light-weight wooden containers of the type employed for storing and/or transporting bulky bakery-products such as loaves of bread or the like.

An object of the present invention is to provide a light-weight, strong, rigid bread-box of the general style and type employed by bakeries for storing and transporting 40 loaves of bread; which box is adapted to be partially dismantled and collapsed or "knocked-down," whereby said box may be stored, when empty, in a fraction of the space required of a non-collapsible bread-box.

Another object of the present invention is to provide a collapsible storage-container which has interlocking means thereon whereby to permit a plurality of said containers or boxes to be stacked upon each other in interlocking relationship whereby said boxes or containers may be neatly and securely piled when fully opened and whereby said pile or stack of boxes will not be disarranged when subjected to a lateral or horizontal force.

Further objects of the present invention will be apparent by reference to the appended specification, claims and drawings.

For the purpose of illustrating the invention, there is shown in the accompanying drawings a form thereof which is at present preferred, although it is to be understood that the various instrumentalities of which the invention consists can be variously arranged and organized and that the invention is not limited to the precise arrangements and organizations of the instrumentalities as herein shown and described.

Referring now to the drawings wherein like reference characters indicate like parts:

Figure 1 represents a top perspective view of the collapsible box of the present invention, showing the box fully extended in its non-collapsed position with the bottom thereof in operative position between the side-members thereof.

Figure 2 represents a top perspective view of the collapsible box of the present invention with the end members thereof in partly collapsed position and with the bottom panel removed therefrom.

Figure 3 represents a bottom perspective view of the bottom panel of the collapsible box of the present invention.

Figure 4 represents an end elevational view of three collapsible boxes of the present invention in stacked interlocked relation to one another.

2

Figure 5 represents a cross-sectional view along line 5—5 of Figure 1.

Figure 6 represents a bottom plan view of the side and end panels of the collapsible box of the present invention, shown in fully folded position.

The collapsible box of the present invention is a generally rectangular, five-sided, open-top inflexible container including two side-panels 10 and 11, centrally split end-panels 12 and 13 and a bottom panel 14.

The side panels 10 and 11 may be fabricated and include the horizontal frame-members or rails 15 and 16 and the vertical frame-members or rails 17 and 18, suitably reinforced at the

corners by the upper and lower buffer-plates or brackets 19 and 20 respectively. A relatively thin sheet-member 21 is rigidly secured to the frame members 15, 16, 17 and 18 in the grooves or rabbets 22 thereof, as shown more clearly in Figure

20 5. The rabbeted joints between the frame members 15, 16, 17 and 18 and the sheet-member 21 provide a smooth uninterrupted interior surface for the side portions 10 and 11, as is evident by reference to Figure 5.

25 The end panels 12 and 13 are centrally split, as at 23 and 24, respectively, to provide separate members 12a, 12b and 13a and 13b. The individual panels 12a, 12b, 13a and 13b may be fabricated of frame and panel members similar to the side panels 10 and 11.

30 The end members 12a and 13b are each pivotally secured to the side panel 10, on the interior surface thereof, by a plurality of hinges 25. The hinges 25 are secured to the side panel 10 and the end panels 12a and 13b whereby the outer surfaces of the frame-members of the end panels 12a and 13b are aligned with the edges of the side panel 10 when the box of the present invention is open to its non-collapsed position, with

35 the end-panels 12a and 13b, at right angles to the side panel 10, as shown in Figure 1. In like manner, the end panels 12b and 13a are pivotally secured to the side panel 11 by a plurality of hinges 26. The hinges 25 and 26 permit the end panels 12, 13b and 12b and 13a, to swing toward and to fold against the side panels 10 and 11 in a juxtaposed and contacting manner, as shown in Figure 6.

40 The end panel 12a is pivotally secured to the end panel 12b by a plurality of hinges 27, secured to the outer surface thereof. In like manner, the end panels 13a and 13b are pivotally interconnected by a plurality of hinges 28 in a manner which permits the central, juxtaposed hinged edges 23 and 24 of the end-panels 12 and 13 to

pivot inwardly about the hinge members 25 and 26 at the corner edges of the panels 10 and 11, respectively. Thus, when the bottom panel 14 is removed from its position between the side members 10, 11, 12 and 13, the end panels 12 and 13 may be folded inwardly as shown particularly in Figure 2, until the inner surfaces thereof abut the inner surfaces of the panels 10 and 11, with the outer surfaces of the panels 12a and 12b touching each other and the outer surface of the panels 13a and 13b adjacent to and in contact with each other. The completely folded side-panels and end-panels are shown in Figure 6.

The hinge members 25, 26, 27 and 28 may be appropriately recessed into the adjoining panel-members to minimize the bulk and thickness of the side-panels and end-panels when in the collapsed position shown in Figure 6.

The bottom panel 14 is generally rectangular in shape and adapted to fit within the space defined by the inner surface of the side-panels 10 and 11 and the end-panels 12 and 13, when said panels are extended to the non-collapsed position shown in Figure 1. Thus the bottom panel 14 may be lowered within the side panels 10, 11, 12 and 13 until the lower surface of the main body portion 29 thereof is aligned with the lower edge of the side and end panels, as shown in Figure 5.

A plurality of angle-brackets or supports 30, of a generally L-shaped configuration, are disposed along and secured to the lower frame-members or rails (such as the frame member 16) of the side-panels 10 and 11 and end-panels 12 and 13, with the horizontal portions thereof extending inwardly beneath the rails and beyond the inner surface of the side and end panels. The brackets 30 are adapted to contact the under surface of the body portion 29 of the bottom panel 14 when the bottom panel 14 is in operative position between the side panels and the end panels.

A plurality of skids or runners 31 and 32 are disposed along the under surface of the bottom panel 14 along the side edges thereof. The runners 31 and 32 are adapted to rest between the L-shaped brackets 30 to afford greater rigidity to the assembled side, end and bottom panels, as well as to provide protective means upon which the bottom of the collapsible box of the present invention may rest when the container is filled with merchandise and placed upon a supporting surface. If desired, appropriate sheathing or protective metallic plates 33 may be secured to the skids or runners 31 and 32 particularly near the ends 34 thereof.

The skids or runners 31 and 32 have a vertical dimension sufficient to permit the runners to protrude beneath the lower edge of the side and ends of the box and particularly below the L-shaped brackets 30, as is shown particularly in Figure 5, so that the lower portion of the skids or runners 31 and 32, may interlockingly engage the inner surface of the upper frame-members or rails (such as the frame member 15) when a plurality of the boxes of the present invention are stacked upon each other in interlocking relationship, as shown in Figure 4. Thus the ends 34 of the runners 32 will contact a portion of the inner surface of the upper frame-member of the end panels 12 and 13 and the side surface 35 of the runners 31 will abut a portion of the inner surface of the upper rail of the side-panels 10 and 11. The skids or runners 31 and 32 provide means for inter-

locking a plurality of boxes, and the containers of the present invention may be superimposed and stacked upon each other and will remain in the inter-engaged position even though subjected to horizontal side-forces (such as the swaying or sliding motion imparted to a plurality of such stacked boxes within a delivery-truck such as a bread-delivery van or the like).

To effect an easy removal of the bottom 14 from the sides and ends 10, 11, 12 and 13, a plurality of finger-holes 36 may be formed therein whereby the bottom-panel 14 may be lifted from the supports 30.

The present invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

Having thus described our invention, what we claim as new and desire to protect by Letters Patent is:

1. A collapsible rigid-walled container including vertical side-members having hinge-members operatively secured to the inner surface thereof in spaced relation to the vertical edges thereof, centrally and vertically split end-members operatively secured along the inner vertical edges thereof to said hinge-members, said end-members pivotally secured along said central vertical split whereby said end-members may be moved inwardly and said side-members simultaneously moved toward each other, a removable bottom-member adapted to be supported between said end-members and side-members by a plurality of brackets extending inwardly from the lower horizontal edges of said side-members and end-members, spacers depending from said bottom-member adapted to extend between and beneath said brackets and said side-members and end-members whereby to rigidify said side-members and end-members when said bottom-member is disposed therebetween and to provide interlocking means adapted to engage the upper horizontal edges of a similar collapsible rigid-walled container aligned therewith to prevent relative horizontal movement therebetween.

2. A collapsible rigid-walled container including vertical side-members comprising panel and frame portions having a flush interior surface, and having hinge-members operatively secured to the inner surface thereof in spaced relation to the vertical edges thereof, centrally and vertically split end-members comprising panel and frame portions having a flush interior surface operatively secured along the inner vertical edges thereof to said hinge-members, said end-members pivotally secured along said central vertical split whereby said end-members may be moved inwardly and said side-members simultaneously moved toward each other, a removable bottom-member adapted to be supported between said end-members and side-members by a plurality of brackets extending inwardly from the lower horizontal edges of said side-members and end-members, spacers depending from said bottom-member adapted to extend between and beneath said brackets and said side-members and end-members whereby to rigidify said side-members and end-members when said bottom-member is disposed therebetween and to provide interlocking means

adapted to engage the upper horizontal edges of a similar collapsible rigid-walled container aligned therebeneath to prevent horizontal movement therebetween.

3. A collapsible rigid-walled container including vertical side-members having hinge-members operatively secured to the inner surface thereof in spaced relation to the vertical edges thereof, centrally and vertically split end-members operatively secured along the inner vertical edges thereof to said hinge-members, said end-members pivotally secured along said central vertical split whereby said end-members may be moved inwardly and said side-members simultaneously moved toward each other until a space of only twice the thickness of said end-members intervenes said side-members, a removable bottom-member adapted to be supported between said end-members and side-members by a plurality of brackets extending inwardly from the lower horizontal edges of said side-members and end-members, spacers depending from said bottom-member adapted to extend between and beneath said brackets and said side-members and end-members whereby to rigidify said side-members and end-members when said bottom-member is disposed therebetween and to provide interlocking means adapted to engage the upper horizontal edges of a similar collapsible rigid-walled container aligned therebeneath to prevent relative horizontal movement therebetween.

4. A collapsible rigid-walled container includ-

ing vertical side-members having hinge-members operatively secured to the inner surface thereof in spaced relation to the vertical edges thereof, centrally and vertically split end-members operatively secured along the inner vertical edges thereof to said hinge-members, said end-members pivotally secured along said central vertical split whereby said end-members may be moved inwardly and said side-members simultaneously moved toward each other, a removable bottom-member adapted to be supported between said end-members and side-members by a plurality of brackets extending inwardly from the lower horizontal edges of said side-members and end-members, with the lower surface thereof flush with the bottom edge of said side-members and end-members, spacers depending from said bottom-member adapted to extend between and beneath said brackets and said side-members and end-members whereby to rigidify said side-members and end-members when said bottom-member is disposed therebetween and to provide interlocking means adapted to engage the upper horizontal edges of a similar collapsible rigid-walled container aligned therebeneath to prevent relative horizontal movement therebetween.
